UNITED STATES PATENT OFFICE.

**CARL ROSENBERGER, OF NEW YORK, N. Y., ASSIGNOR TO COHN & ROSENBERGER, INC.,
OF NEW YORK, N. Y., A CORPORATION OF NEW YORK.**

DESIGN FOR A RING.

48,608.

Specification for Design.

Patented Feb. 22, 1916.

Application filed December 11, 1915. Serial No. 66,382. Term of patent 7 years.

To all whom it may concern:

Be it known that I, CARL ROSENBERGER, a citizen of the United States, and a resident of the city, county, and State of New York, have invented a new, original, and ornamental Design for Rings, of which the following is a specification, reference being had to the accompanying drawing, forming part thereof.

Figure 1 is a front elevation of a ring, showing my new design; Fig. 2 is a side elevation of the same; Fig. 3 is a rear elevation of the same; and Fig. 4 is a plan view of the same.

I claim:

The ornamental design for a ring, as shown.

CARL ROSENBERGER.
